UNITED STATES PATENT OFFICE.

EDWARD SCHMIDT, OF EL PASO, TEXAS.

COMBINED RULER AND BLOTTER.

1,105,002.

Specification of Letters Patent. Patented July 28, 1914.

Application filed October 27, 1913. Serial No. 797,641.

To all whom it may concern:

Be it known that I, EDWARD SCHMIDT, a citizen of the United States of America, and resident of El Paso, in the county of 5 El Paso and State of Texas, have invented certain new and useful Improvements in Combined Rulers and Blotters, of which the following is a specification.

This invention relates to means for ruling and blotting the lines ruled and has for 10 its object the provision of novel means for combining a ruler and blotter in a compact and easily manipulated form, the invention being furthermore of utility for tearing 15 paper on a line parallel with the ruling edge.

A further object of this invention is to provide a device of the character indicated which can be manufactured by a simple 20 process of stamping and bending, making it possible to construct the body of the device from sheet metal appropriately trimmed to produce a finished appearance and such artistic effect as may be necessary 25 or desirable for the trade.

A still further object of the invention is to produce a device of the character indicated, possessing advantages in points of 30 simplicity, efficiency and durability, proving at the same time comparatively inexpensive to manufacture.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification, 40 wherein like characters denote corresponding parts in the several views, and in which—

Figure 1 illustrates a fragment of a book and the invention by a view in perspective 45 applied thereto; Fig. 2 illustrates a sectional view of the device forming the subject matter of the invention, on the line 2—2 of Fig. 1, the book being omitted; and Fig. 3 illustrates a sectional view on the line 3—3 of Fig. 1, omitting the book.

In these drawings, I have illustrated the invention as comprising a plate 4 having one edge standing at right angles thereto as shown at 5 and designed as a hand grasp

to be used by the operator for manipulating 55 the device. The front of the plate extends diagonally upward as at 6 and terminates in a downwardly extending lip 7 and the edge of the downwardly extended portion 7 terminates above the plane of the plate 4, 60 thus causing the said front edge to stand above the surface of the paper or base on which the plate may rest. I have furthermore provided for supporting the ruling edge formed by the lip 7 above the plane 65 of the surface being ruled by interposing between the plate and the surface being ruled the blotters 8' which may be of any desired number or thickness.

As a means for retaining the blotters in 70 place so that they may be carried or moved with the plate 4, the ends of the plate are bent to form the flanges 8 and 8^a which underlie the plate 4, but are spaced therefrom to form seats for the said blotters. 75 By reason of the arrangement for assembling the blotters with relation to the plate, the ruling may be done by running the pen along the edge of the lip 7 and, by a slight movement of the ruler, the blotting 80 surface may be caused to contact the freshly inked line, so that the excess ink may be absorbed by the blotter.

For the purpose of giving a finished appearance to the device, a facing strip 10 85 having flanges 9 covers the plate 4 and extends up the side of the flange 5, the said facing strip also extending under the flanges 8 and 8^a.

The upper edge of the flange 5 is formed 90 by bending the metal on itself to form a bead 11, producing a more rigid member for the hand grasp and giving a finished effect to the said edge, due to the curved configuration afforded by overlapping the said 95 portions.

By reason of the fact that the lip 7 is of metal, the said lip may be used for tearing paper, as sufficient pressure can be exerted on the paper by the lip by tilting the plate 100 4 to insure severance of the paper on the line of the lip when the same is in contact with the paper.

This invention has been found of great utility in bookkeeping and other pursuits 105 and it is obvious that modifications may be made in the proportions without departing from the scope of the appended claim.

I claim—

In a ruler, a plate having an upstanding flange at its rear side, said upstanding flange constituting a hand grasp, flanges at the 5 ends of the plate, said flanges being turned under and extending parallel with the under surface of the plate but spaced therefrom, absorbent material having its edges inserted between the flanges and the plate, the front 10 of said plate having a diagonally upwardly

extending portion and an integral downwardly extending lip carried by the upwardly extended portion.

In testimony whereof, I affix my signature in the presence of two witnesses.

EDWARD SCHMIDT.
